UNITED STATES PATENT OFFICE.

WILLIAM EDWIN WOLFE, OF WILDER, VIRGINIA.

SWITCH SYSTEM FOR MINE LOCOMOTIVES.

1,413,250.

Specification of Letters Patent. Patented Apr. 18, 1922.

Application filed April 28, 1920. Serial No. 377,324.

To all whom it may concern:

Be it known that I, WILLIAM E. WOLFE, a citizen of the United States, residing at Wilder, in the county of Russell and State 5 of Virginia, have invented a new and useful Switch System for Mine Locomotives, of which the following is a specification.

This invention has reference to a switch system for mine locomotives and its object is 10 to simplify the system so that liability of burn-outs is reduced or eliminated and expensive delays are prevented.

It is customary in mines to provide the main lines of travel with trolley lines and 15 to branch off rooms or passageways in which the coal is being mined. In such rooms tracks for the mine locomotives are laid, but the trolley lines are not continued. However, electric current is needed for driving 20 the mine locomotives in order that the empty cars may be moved into the rooms and filled cars may be withdrawn therefrom. To accomplish this, the mine locomotive is provided with a reel paying out an electric 25 conductor as the locomotive moves into the room from the main trolley line and taking up the conductor as the locomotive again moves toward the trolley line. Under some conditions the trolley lines are arranged 30 sometimes on one side of the track and sometimes on the other and consequently double trolley poles are employed.

It is customary to provide the locomotive with a two-way switch whereby the locomotive 35 may receive current from either the trolley pole or the reel cable. Such switches have been found to be liable to burn-outs or other such damage, and in the confines of a mine and the very restricted space available, 40 serious accidents happen to the workmen from contact with the switches.

It is the object of the invention to wholly 45 eliminate such switches which are not only a source of danger and inconvenience but are relatively costly structures, and for this purpose, the trolley pole or poles are so constructed that they replace the switches, making it possible to preserve the continuity of the electric circuit, even though the trolley 50 pole be removed from engagement with the trolley wire. In carrying out the invention, the trolley pole is removed from engagement with the trolley wire and mechanically and electrically engaged with a retaining 55 hook which latter is electrically connected to one end of the flexible conductor on the

gathering reel, while the other end of the conductor is furnished with a hook or some connecting means which may be electrically applied to the trolley wire in such manner as 60 to be retained thereby. In this way, current is supplied to the motive means of the electric locomotive through the usual controller, the flexible conductor being withdrawn from the gathering reel as the locomotive moves 65 away from the portion of the mine provided with the trolley wire, with the trolley pole serving as the sole switch means and doing away with the customary electrical switch heretofore employed for the purpose. 70

The invention will be best understood from a consideration of the following detailed description taken in connection with the accompanying drawings forming part of this specification, with the understanding, 75 however, that the invention is not confined to any strict conformity with the showing in the drawings, but may be changed and modified so long as such changes and modifications mark no material departure from the 80 salient features of the invention as expressed in the appended claims.

In the drawings,

Fig. 1 is a side elevation, more or less diagrammatically shown, of a mine locomotive equipped with the invention and showing the trolley pole utilized as a switch. 85

Fig. 2 is a view similar to Fig. 1, but showing the trolley pole in position to directly receive current from the trolley wire. 90

Fig. 3 is a diagrammatic plan view of the mine locomotive, showing two trolley poles and omitting the gathering reel, but showing the collecting ring for the gathering reel. 95

Referring to the drawings, there is shown a mine locomotive 1 which may be of ordinary construction and is therefore only indicated in outline without any attempt to illustrate particular detail. The locomotive is indicated as provided with the usual controller 2 and is supplied with a gathering reel 3 having the customary collecting ring 4, best shown in Fig. 3. As these parts do not enter specifically into the invention, no attempt is made to illustrate them except in 100 a general way.

Mounted on the locomotive 1 is a trolley pole 5 or two trolley poles 5 and 6, the latter being shown in Fig. 3. The trolley pole or poles are each carried by a support 7 to 110 which it is connected and each trolley pole is indicated as urged upwardly by a spring

8. Each trolley pole carries the usual trolley wheel 9, and as this trolley wheel may be of ordinary construction, no particular description thereof is needed. The trolley wheel 9 is so located that it may be placed in contact with a trolley wire 10 when needed or withdrawn therefrom. When a trolley pole is withdrawn from the trolley wire 10, it may be moved, against the tendency 5 of the spring 8, toward the top of the locomotive 1 and then caught under a retaining hook 11 so as to be supported in close relation to the locomotive and thus held out of the way.

15 The gathering reel shown generally at 3, is in the form of a spool 12 which may be of ordinary construction and therefore needs no particular description. The gathering reel is for the purpose of carrying a conducting wire 13 electrically connected at one end to the collecting ring 4, which may be located on top of the locomotive, and at the other end provided with a hook 14 or other suitable device whereby the conductor 13 20 may be made fast to the trolley wire 10, as, for instance, at a trolley wire hanger 15, so that the electrical connection is established between the trolley wire 10 and the conductor 13.

25 30 The hook or hooks 11 are each carried by an insulating block 16, so that the hook itself is insulated, and one hook, in case two hooks are employed, is connected by a conductor 17 to the collecting ring 4. A trolley pole, say the trolley pole 5, is connected by a conductor 18 to the controller 2, which latter is connected in the customary manner with the locomotive motor, not shown.

35 In the case of two trolley poles 5 and 6 40 being used, the hook for retaining the trolley pole 5 in the lowered position is connected by a conductor 19 to the trolley pole 6, and the first hook 11 is connected by another conductor 17^a to a brush 20 engaging the 45 collecting ring 4 so that with both trolley poles held down by the hooks 11 a circuit is established from the controller 2 through the conductor 18 to the trolley pole 5, hook 11 engaging it, conductor 19, trolley pole 6, hook 11 engaging the trolley pole 6, conductor 50 17^a, brush 20 and collecting ring 4 through the conductor 13 and hook 14 to the trolley wire 10, where but one trolley pole is employed, the circuit is by way of the 55 controller 2, conductor 18, trolley 5, hook 11, conductor 17, brush 20, conductor 13 and hook 14, to the trolley wire 10.

60 In either instance, the customary cut-out switch universally used in mine locomotives is eliminated and the expense of such a switch and its installation, as well as the danger of such a switch to operators, is wholly avoided. The switch is replaced by the customary trolley pole which must be 65 present, whether or not the switch be pres-

ent, whereby the installation is simplified to a corresponding extent.

What is claimed is:—

1. An electric mine locomotive provided with trolley current-collecting means, a gathering reel and conducting wire thereon capable of being payed out from the reel and re-wound thereon, and holding means for the trolley current-collecting means electrically connected to the conducting wire 70 on the reel whereby the trolley current-collecting means may be utilized as an electric switch and thereby be included in the energizing circuit of the electric locomotive 75 when the trolley current-collecting means is removed from the trolley conductor.

2. An electric mine locomotive provided with a controller and with trolley pole current-collecting means, a gathering reel on the locomotive having a flexible conductor 80 thereon capable of being payed out from and wound upon the reel for electrical connection with a line conductor, a trolley pole hook or retainer on the locomotive for holding the pole away from the line conductor, and electrical connections between the hook and the flexible conductor on the reel whereby the trolley pole structure constitutes an electrical switch for connecting 85 the line conductor and flexible conductor 90 on the reel to the locomotive controller structure.

3. An electric mine locomotive provided with a trolley pole and controller to which the pole is connected, a gathering reel with 100 a conducting wire thereon for connection to a trolley wire, and a retaining device on the locomotive for holding the trolley pole away from the trolley wire, the retaining device having electrical connection with the wire 105 on the reel, whereby when the trolley pole is withdrawn from the trolley wire it constitutes an electric switch for coupling the wire on the reel to the controller.

4. A mine locomotive provided with a 110 gathering reel carrying a feeding conductor, a controller, a trolley pole on the locomotive connected to the controller, an insulated device for holding the trolley pole away from the trolley wire and at the same 115 time making electrical contact with the trolley pole, and electrical connections between the insulated holding device and the feeding conductor on the reel, whereby the trolley pole, when depressed, serves as a switch 120 for coupling the feeding conductor to the controller on the locomotive.

5. A mine locomotive provided with a gathering reel, a feeding conductor on the gathering reel provided with means for 125 electrically connecting it to a trolley wire, a trolley pole on the locomotive, a controller to which the trolley pole is electrically connected, an insulated hook on the locomotive for holding the trolley pole down, and elec- 130

trical connections between the insulated hook and the feeding conductor on the reel, whereby the trolley pole may be utilized as an electrical switch member for electrically coupling the feeding conductor on the reel to the controller on the locomotive.

6. A mine locomotive provided with a gathering reel, a feeding conductor thereon with means for connecting it to a trolley wire, trolley poles, one on each side of the locomotive, insulated holding hooks for the trolley poles individual thereto and carried

by the locomotive, a controller on the locomotive, electrical connections between the controller and one of the trolley poles, electrical connections between the holding hook for said trolley pole and the other trolley pole, and electrical connections between the holding hook for the second trolley pole and the feeding conductor on the reel.

In testimony, that I claim the foregoing as my own, I have hereto affixed my signature.

WILLIAM EDWIN WOLFE.
